CLAIM

The ornamental design for a transition for vinyl tile and carpet tile, as shown and described.

DESCRIPTION

FIG. 1 is a front perspective view of a first embodiment of a transition for vinyl tile and carpet tile showing our new design;

FIG. 2 is top plan view thereof;

FIG. 3 is a front elevation view thereof;

FIG. 4 is a side elevation view thereof;

FIG. 5 is a rear elevation view thereof;

FIG. 6 is a bottom plan view thereof;

FIG. 7 is an opposite side elevation view of FIG. 4;

FIG. 8 is a perspective view of a second embodiment of a transition for vinyl tile and carpet tile showing our new design;

FIG. 9 is a top plan view thereof;

FIG. 10 is a front elevation view thereof;

FIG. 11 is a side elevation view thereof;

FIG. 12 is a rear elevation view thereof;

FIG. 13 is a bottom plan view thereof; and,

FIG. 14 is an opposite side elevation view of FIG. 11.

The transition for vinyl tile and carpet tile is shown with a symbolic break in its length. The appearance of any portion of the article between the break lines forms no part of the claimed design.
